(57) **CLAIM**

The ornamental design for a tire tread, as shown and described.

DESCRIPTION

FIG. 1 is a perspective view of a tire tread of the present application taken generally from the front and a first side of the tire;

FIG. 2 is a front view thereof, and any top, bottom, or rear view would be the same as the front view;

FIG. 3 is a side view of the first side thereof;

FIG. 4 is an enlarged partial, perspective view taken generally from the front and the first side thereof;

FIG. 5 is an enlarged, partial front view thereof;

FIG. 6 is an enlarged, partial side view of the first side thereof;

FIG. 7 is a perspective view of a tire including the tire tread of the present application taken generally from the front and a second side of the tire;

FIG. 8 is a side view of the second side thereof;

FIG. 9 is an enlarged partial, perspective view taken generally from the front and the second side thereof; and,

FIG. 10 is an enlarged, partial side view of the second side thereof.

The outermost broken line on each of the tire sidewalls depicts the boundary of the claim. The broken lines depict subject matter that forms no part of the claimed tire tread design, and are included for the purpose of illustrating the full tire. The tread pattern is understood to repeat uniformly throughout the circumference of the tire.

1 Claim, 10 Drawing Sheets
